United States Patent Office

Des. 224,803
Patented Sept. 19, 1972

224,803

WRISTWATCH

Charles P. Knauft, 13824 Oxnard St.,
Van Nuys, Calif. 91406

Filed Apr. 22, 1971, Ser. No. 136,646

Term of patent 7 years

Int. Cl. D10—02

U.S. Cl. D42—8

FIG. 1

FIG. 3

FIG. 2

FIG. 1 is a top plan view of a wristwatch showing my new design;

FIG. 2 is an end elevational view, the opposite end being a mirror image thereof; and

FIG. 3 is a side elevational view the opposite side being the same in appearance except for the absence of a crown.

I claim:

The ornamental design for a wristwatch, as shown and described.
